INVENTOR.

BY *John M. Spellman*
ATTORNEY.

UNITED STATES PATENT OFFICE.

HERBERT J. HANDS, OF DALLAS, TEXAS.

DESIGN FOR AN AUTOMOBILE-LENS.

58,146.

Specification for Design. Patented June 14, 1921.

Application filed January 12, 1920. Serial No. 351,059. Term of patent 3½ years.

To all whom it may concern:

Be it known that I, HERBERT J. HANDS, a citizen of the United States, residing at Dallas, in the county of Dallas and State of Texas, have invented a new, original, and ornamental Design for an Automobile-Lens, of which the following is a specification, reference being had to the accompanying drawing, forming parts hereof.

The figure is a plan view of an automobile lens, showing my new design.

I claim:

The ornamental design for an automobile lens as shown.

HERBERT J. HANDS.

Witness:

F. S. DEERING.
